Patented Oct. 21, 1919.

Inventor

R.H. Reynolds

By Watson E. Colman
Attorney

UNITED STATES PATENT OFFICE.

RECTOR HUNEFORD REYNOLDS, OF WOODRIVER, ILLINOIS, ASSIGNOR OF ONE-HALF TO
FRANK GINGER, OF ALTON, ILLINOIS.

ANCHOR.

1,319,419.

Specification of Letters Patent. Patented Oct. 21, 1919.

Application filed July 30, 1919. Serial No. 314,237.

To all whom it may concern:

Be it known that I, RECTOR HUNEFORD REYNOLDS, a citizen of the United States, residing at Woodriver, in the county of Madison and State of Illinois, have invented certain new and useful Improvements in Anchors, of which the following is a specification, reference being had to the accompanying drawings.

10 This invention relates to certain improvements in anchors, and it is an object of the invention to provide a novel and improved device of this general character comprising metallic plates formed and assembled in a manner whereby the anchor possess a maximum of strength.

20 The invention consists in the details of construction and in the combination and arrangement of the several parts of my improved anchor whereby certain important advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying drawings, wherein:

30 Figure 1 is a view in top plan of an anchor constructed in accordance with an embodiment of my invention, the shank being shown in section.

35 Fig. 2 is a sectional view taken through the device as illustrated in Fig. 1, with the shank in elevation.

40 Fig. 3 is a fragmentary sectional view illustrating in detail the attachment of an arm of the inner plate with the main plate of the anchor.

45 As disclosed in the accompanying drawings, P denotes a concavo-convex metallic plate of desired dimensions and preferably in the form of a four pointed star the central portion 1 of which constituting a head and the points 2 constituting the flukes.

50 In order to materially strengthen and reinforce the plate P said plate is provided with a pair of perpendicularly related corrugations 3 opening inwardly, each of the corrugations 3 extending entirely across the plate P and from the outer extremities of diametrically opposed points or flukes 2.

55 Arranged inwardly of the head portion 1

of the plate P is a second plate P', said plate being flat and preferably rectangular. Each corner portion of the plate P' is provided with an angularly extending flat arm 4 contacting with the inner or concave face of a point or fluke 2 and bridging the corrugations 3 extending along said point or fluke. The arm 4 is riveted as at 5 or otherwise secured to the plate P at opposite sides of the corrugation 3.

60 6 denotes a shank of desired length and has its inner end portion disposed through the central portions of the plates P and P' and held in applied position in any desired manner. The outer end of the shank 6 is 70 provided with an eye 7 to afford convenient attaching means.

65 From the foregoing description, it is thought to be obvious that an anchor constructed in accordance with my invention is 75 particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my 80 invention in practice except as hereinafter claimed.

I claim:

1. An anchor consisting of a concavo-convex plate having a plurality of angularly related ribs extending substantially thereacross and a flat plate arranged inwardly of the central portion of the first named plate, the corners of said second named plate being provided with arms, and means for 90 securing said arms to the concave face of the first named plate.

2. An anchor comprising a concavo-convex plate provided with angularly related corrugations extending substantially entirely 100 thereacross, and a flat plate positioned inwardly of the central portion of the first named plate and provided with arms contacting with the convex face of the first named plate and bridging the corrugations 105 therein, and means for securing said arms to the first named plate at opposite sides of the corrugations.

3. An anchor consisting of a concavo-convex plate having a plurality of angularly re- 110

lated ribs extending substantially there-across and a flat plate arranged inwardly of the central portion of the first named plate, the corners of said second named plate being provided with arms, means for securing said arms to the concave face of the first named plate, and a shank extending outwardly from the convex face of the first

named plate and through the second named plate.

10

In testimony whereof I hereunto affix my signature in the presence of two witnesses.

RECTOR HUNEFORD REYNOLDS.

Witnesses:

PHILIP FORCADE,

J. W. COOPER.
